UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

COMPOSITE BIT.

Application filed March 8, 1923. Serial No. 623,587.

To all whom it may concern:

Be it known that I, CHARLES C. HANSEN, a citizen of the United States, a resident of Easton, county of Northampton, and State 5 of Pennsylvania, have invented a certain Composite Bit, of which the following is a specification accompanied by drawings.

This invention relates to core drills and particularly to the bits used for cutting more 10 or less solid cores of rock or other material in the operation of such drills. Various types of bits have been employed with core drills in which types loose chilled shot or other abrasive material usually constitutes 15 the cutting element. Shot bits using such chilled shot or other material are subject to considerable wear and require renewal from time to time, and the handling of the loose shot also entails care in the operation of 20 the drill.

The primary object of this invention is to enable a core drill to be equipped with a removable bit having a renewable cutting element in which abrasive cutting material 25 is embedded in a cementitious binder, the whole being in a solid mass so that the use of loose shot is obviated.

A further object of the invention is to simplify and improve the construction of 30 the renewable cutting bits and to permit a new cutting element to be substituted when one has been worn down.

With the above and other objects in view my invention consists in the features of construction and operation described in the following specification and illustrated on the accompanying drawings, forming a part 35 hereof, in which—

Figure 1 is a longitudinal sectional elevation of a core drill equipped with my device; and

Figure 2 is a transverse section on the line 2—2 of Figure 1.

Referring to the drawings, I have illustrated the essential parts of a typical Calyx core drill, in which the rotary drill rod A is secured to the core barrel plug B, as by means of screw threads. The hollow cylindrical core barrel C is threaded to the lower 50 end of the plug B and a water tube D is threaded to the upper end of the plug B. The core barrel C receives the core E in the usual manner.

The core barrel C is equipped with a detachable cutting bit, and in the present in-

stance my improved bit includes a cylindrical body portion F adapted to be threaded to the lower end of the core barrel C as shown at G so that the outer surface is substantially flush with the outer surface of the 60 core barrel C. The body F is provided with a depending annular cylindrical portion H, and inner and outer concentric cylinders J and K respectively are adapted to be removably secured on opposite sides of the 65 central portion H. These cylinders J and K together constitute an extension of the body portion F, of substantially the same diameter as the body F and the core barrel C. In the present instance the cylinders J and K 70 are secured to the portion H by rivets L countersunk below the outer surfaces of the cylinders J and K.

An annular chamber O of uniform diameter is formed between the cylinders J and K 75 below the body portion F and portion H. This chamber is adapted to contain a mass of abrasive cutting material P and a binder introduced therein in any suitable manner so that the cylinders J and K and material P 80 constitute a unitary cutting element. In this case the abrasive material is a composition including cement and small broken pieces of crushed chilled steel, or chilled steel shot, or other hard substance. 85

The cylinders J and K have a plurality of pairs of oppositely disposed openings or holes Q which preferably extend completely through the walls of the cylinders J and K. The cementitious abrasive mixture 90 is introduced into the chamber O so that the mixture enters the openings Q. When the mixture has hardened, the mass will be securely held between the cylinders J and K and anchored by the portions which fill the 95 openings Q.

The cylinders J and K and the cementitious mass P form a unitary cutting element and wear down together. During the drilling, the abrasive cutting material is released from the cement or other binder and is acted upon by the rotating cutting element in the same manner as loosely inserted shot beneath a shot bit, except that the cutting material embedded between the cylinders J and K is itself abrasive and may assist in cutting the material being drilled. 100

When the cylinders J and K and the abrasive mixture have been worn down completely, the body F is unscrewed from the 110

core barrel C and replaced with a new bit. The cylinders J and K may also be removed from a worn bit and new cylinders riveted thereon, the space between the cylinders being filled with the abrasive composition.

I claim:

- In a core drill, the combination of a core barrel and a cutter bit detachably secured to said core barrel, said cutter bit comprising 10 a hollow cylindrical body portion internally threaded for attachment to the core barrel and having a depending annular cylindrical portion, inner and outer cylinders substan-

tially flush with the inner and outer surfaces of said body portion and riveted to said depending portion, and a mass of abrasive and cementitious material between said cylinders, said cylinders having openings extending therethrough for anchoring said mass of abrasive and cementitious material, said 15 cylinders and said mass of material together constituting a replaceable cutting element for said core drill.

In testimony whereof I have signed this specification.

CHARLES C. HANSEN.
